UNITED STATES PATENT OFFICE.

JOHN H. GOSS, OF WATERBURY, CONNECTICUT, ASSIGNOR TO THE SCOVILL MANUFACTURING COMPANY, OF SAME PLACE.

DESIGN FOR A HEAD AND SHANK MEMBER FOR BICYCLE-PUMPS.

SPECIFICATION forming part of Design No. 28,872, dated June 14, 1898.

Application filed March 7, 1898. Serial No. 673,016. Term of patent 7 years.

To all whom it may concern:

Be it known that I, JOHN H. GOSS, of Waterbury, in the county of New Haven and State of Connecticut, have invented a new 5 Design for a Head and Shank Member of a Swivel Connection for Bicycle-Pumps; and I do hereby declare the following, when taken in connection with the accompanying drawing and the letters of reference marked thereon, to be a full, clear, and exact description 10 of the same, and which said drawing constitutes part of this specification and represents a perspective view of a head and shank member of a swivel connection for bicycle-pumps 15 embodying my design.

This invention relates to a design for a head and shank member of a swivel connection for bicycle-pumps; and the design consists in the configuration as hereinafter described, and 20 shown in the accompanying illustration.

As herein shown, the head A has a rounded top and four sides, two of which are slightly rounded, and the other two sides, opposite to each other, are flat. The shank B, which depends from the head, is corrugated or ribbed, 25 and through the head and opening on the flat sides thereof is a passage C at right angles to the plane of the said shank.

I claim—

The design for a head and shank member 30 of a swivel connection for bicycle-pumps as shown and described.

In testimony whereof I have signed this specification in the presence of two subscribing witnesses.

JOHN H. GOSS.
